United States Patent Office.

JAMES POTTER, OF PORTLAND, MAINE.

Letters Patent No. 93,118, dated July 27, 1869.

IMPROVEMENT IN SPRING-BED BOTTOM.

The Schedule referred to in these Letters Patent and making part of the same.

To all whom it may concern:

Be it known that I, JAMES POTTER, of Portland, in the county of Cumberland, and State of Maine, have invented a new and useful Improved Bed; and I hereby declare the following to be a full, clear, and exact description thereof, which will enable others to make and use my invention, reference being had to the accompanying drawings, forming part of this specification, in which—

Figure 1 shows a top view of the bed-bottom.

Figure 2, a top view of the flexible connections between the springs and the rods connected to the slats.

A is a view of one of the flexible connections.

B is a view of the button in the end of the slat to engage and hold the rods *a*.

C shows another method of holding the rods *a*.

D is a modification of B.

Same letters show like parts.

e shows the side of the bed-frame.

d the ends.

b the slats of the bed.

Upon the ends *d* are set the wooden rods *e*, secured by metal clamps, *h*.

Around the rods are coiled the springs *f*, as seen in the drawings, the ends of such springs being driven or set into the wood of *d*.

These springs are fitted with hooks at the free end of the wire, to enter the holes in the flexible connections A.

The rods *a* pass under the ends of the slats *b*, and also unite by means of hooks on their ends, with the flexible connections A. (See fig. 2.)

The rods *a* are connected with the slats *b*, in either of the following methods, viz, as at C, where they are fitted into recesses as there shown, or as at D, where a small stud has a projecting head to receive the rods.

Another method is, as shown at B, where the stud *B* slips through the slat so as to make the slat re-

versible, that is so that the rods *a* can be attached to either end of B, the end which is downward always dropping down as far as the button on the upper end will allow it, as seen at B in the drawings.

The slat, as seen at D, is also reversible, but the pin or bolt therein is fixed, and does not drop as at B.

I do not claim the arrangement of the slat-spring and strap, as shown in J. L. Whipple's patent, October 25, 1859, and numbered 25,924. Neither do I claim in combination with the bed-slat a wire-spring having two parallel coils at the base, and two at the top, the one turning adversely to the other. Neither do I claim a hook or hinge in combination with the two adverse springs. Neither do I claim a combination of a cross-bar, rod, pin, and slat with these two springs, as shown in I. Barnes' patent, July 17, 1866, No. 50,484. Neither do I claim a spring bed-bottom composed of a series of wooden slats, connected near their ends by strips having wire-springs attached to the head and foot-pieces of the frame, and connected to the strips centrally between the slats, as in H. H. Palmer's patent, January 15, 1867, No. 61,242. Neither do I claim the combination of two springs, one placed under the other, and operating together, as shown in L. R. Bradbury's patent, April 7, 1868, No. 76,296. Neither do I claim connecting slats by flexible connections; but

What I do claim, and desire to secure by Letters Patent, is—

The combination and arrangement of the springs *f*, constructed as shown, with flexible connections, A, the reversible-fastenings D, B, and the rods *e*, secured by the metal clamps *h*, for the purposes described.

JAMES POTTER.
